UNITED STATES PATENT OFFICE.

HUBERT MEREDITH-JONES, OF NEW YORK, N. Y.

SAFETY CENTRIFUGAL PERCUSSION BASE FUSE.

1,336,701.

Specification of Letters Patent. Patented Apr. 13, 1920.

Application filed June 13, 1917. Serial No. 174,590.

To all whom it may concern:

Be it known that I, HUBERT MEREDITH-JONES, a subject of the King of Great Britain, and resident of New York, N. Y., have 5 invented certain new and useful Improvements in Safety Centrifugal Percussion Base Fuses, of which the following is a specification.

My invention relates to safety fuses for 10 shells and concerns particularly a percussion base fuse.

The invention consists in the features, combination and arrangement of parts herein-after described and particularly pointed out 15 in the claims..

In the accompanying drawings;

Fig. 1 is a sectional view of the fuse.

Fig. 2 is a plan view.

Fig. 3 is a side view of the screw cap.

20 Fig. 4 is a bottom plan view of the screw cap.

Fig. 5 is an elevation of the inside face of one of the sections of the primer cage.

Fig. 6 is a plan view of the part shown in 25 Fig. 5.

Fig. 7 is a side view of the check thimble.

Fig. 8 is a plan view of the check thimble.

Fig. 9 is a plan view of the primer cup.

30 Fig. 10 is a sectional view of the primer cup.

Fig. 11 is a plan view of the primer plate.

Fig. 12 is a plan view of a clip spring.

Fig. 13 is a sectional view of another form of the fuse.

35 Fig. 14 is a view of a different form of the invention.

In these drawings 1 indicates the fuse body having a screw-threaded portion adapted to screw threads in the base of the 40 shell and having a head 15, which is provided with openings 16 to receive a wrench. This body or shell at its inner end is screw-threaded internally and receives a cap 17 which is screw-threaded to fit the interior 45 screw threads on the body or shell, said cap having a shoulder at 18 resting against the edge of the casing or body. Within the casing is mounted a primer cage consisting of two members 19 generally of semi-circular 50 form, each member having a recess or chamber therein at 20 and each having a neck 21 with a recess 22 therein. These members of the primer cage are held together yieldingly by spring clips 23, there being two of these clips fitted to the same groove formed in the outer side of the members of the primer cage. These clips are

formed with lugs which fit into openings in the parts of the cage, one of which openings is indicated at 23^a. Within the primer cage 60 a primer cup 24 is arranged, this consisting of a thin shell having a drawn or swaged projection 25 on its interior. This cup contains the primer material and its inner side is covered by a primer plate 65 26. The neck portion of the primer cage receives the firing pin 27 which is formed integrally with the screw cap or may be formed separately therefrom and secured thereto. This firing pin has a rounded or 70 conical end opposite the primer plate. The cage is of smaller diameter than the interior of the casing or main body of the fuse and it is held in position with its bottom portion 28 normally above the bottom of the 75 body of the fuse, a spring 29 seated in a pocket of the cage and a pocket in the bottom of the main casing serving to press the cage normally away from the bottom of the casing. Surrounding the primer cage is a 80 check thimble 30 formed of sheet metal and of cylindrical shape with its ends provided with inwardly turned flanges 31 and 32.

Openings 33 are formed through the screw cap at several points around the center and around the firing pin, these openings leading from the interior of the casing to the outside and a drive pin 34 carried by the firing pin and extending transversely thereof has its ends lying between the sections of the primer cage. The normal position of the parts is indicated in Fig. 1, from which it will be noticed that the members of the primer cage are pressed together by the spring clips and the neck of the cage fits 90 closely about the firing pin and the primer cage is held at a slight distance away from the bottom of the body or casing 14. When the shell is fired from the gun the first effect is the movement of the cage with respect to 95 the body or casing of the fuse and toward the bottom or outer end thereof, this action being due to the inertia of the cage and being permitted by the spring 29 and also by the sliding fit between the exterior face 100 of the cage and the flanges of the check thimble and it will here be noticed that this check thimble is prevented from following the movement of the cage toward the bottom or outer end of the main casing or body, 110 because the thimble rests on a shoulder 35 formed on the interior face of the casing. The movement of the cage in respect to the casing will bring a groove 36 of the cage

opposite the outer or lower flange 31 of the check thimble and will also bring the shoulder 37 of the cage below the upper flange 32 of the thimble and because of the 5 rapid revolution of the shell and all parts of the fuse due to the rifling of the gun, centrifugal force will be brought into play and the members of the primer cage will fly outwardly away from each other and to- 10 ward the wall of the main body, this action being permitted because as just stated the groove 36 is now located opposite the lower flange 31 of the thimble and the shoulder 37 is located outside of or below the upper 15 flange 32. The members of the cage having thus separated because of the centrifugal force and because the spring clips yield to permit this action the two members of the cage will be locked in their altered position 20 by the flanges 31 and 32 engaging respectively the wall of the groove 36 and the shoulder 37 and the parts will remain in this position during the flight of the projectile until the impact of the same with the 25 object aimed at takes place at which time the cage will fly forwardly in respect to the casing and the firing pin will then act upon the primer and ignition will take place and the fire passing out through the openings 33 30 will be communicated to the explosive in the shell and the explosion will take place.

It may be noted here that when the members of the cage are in normal position, that is held toward each other by the spring 35 clips, the inner or upper end of the neck of the cage members will engage beneath a shoulder 38 adjacent the firing pin but when the members of the cage are separated these neck portions will stand laterally out be- 40 yond the said shoulder or in other words out of line therewith, so that no obstruction will be offered by these shoulders to the free forward movement of the cage members.

Furthermore, when the cage members are 45 separated ample space is provided around the firing pin for the passage of the fire from the primer through the neck portions of the cage members alongside the firing pin and thence through the openings 33 in 50 the shell.

It may be further pointed out that the thimble 30 while fitting against the inner wall of the casing or body sufficiently tight to hold the cage members locked in their re- 55 tracted positions after the said members have set themselves against the bottom of the casing this contact of the thimble with the inner wall of the casing is such that the thimble can be carried forward with the 60 members of the cage when this flies forwardly as a result of the shell striking the object aimed at.

It will be seen from the above that normally the cage is in the condition and in the 65 position illustrated in Fig. 1, that is, its

members are closed and are held in advance of or away from the bottom of the casing and when the projectile is fired from the gun the cage sets itself against the bottom of the body of the fuse where it is locked by 70 engagement with the thimble, the parts of the cage having separated under the centrifugal force and the next action takes place when the impact of the projectile against the object aimed at occurs, whereupon the 75 cage will fly forwardly and cause the primer to be thrown into contact with the firing pin, resulting in the firing of the charge, as above set forth.

I show in Fig. 13 a modification of the 80 invention in which the parts of the cage are held by two sets of spring clips 23^a and in this form also the screw cap is not em- 85 ployed and the firing pin is supported independently of the body or casing of the fuse, this figure illustrating the fact that my invention may be embodied in different forms while adhering to the underlying principles involved in the invention.

Briefly stated the cycle of operation in- 90 volved in this invention is (first) the axial movement of the cage members toward the bottom or outer end of the fuse body; (next) their radial separation and their retention in this axially and radially displaced position 95 by means of the thimble and the centrifugal force arising from the action of the rifling, keeping the parts out in contact with the thimble, and (finally) the forward axial movement of the cage members while re- 100 maining radially separated and thereby the striking of the primer against the firing pin.

In Fig. 14 I illustrate the fact that the invention may be embodied in a form in which the primer 24^a instead of being 105 mounted in the cage or carrier is mounted in a recess in the head of the casing. The carrier of sectional form shown at 19^a has the firing pin mounted thereon, this firing 110 pin being divided longitudinally with one of its members mounted on the sections of the carrier. The carrier also is provided with extensions 19^a normally resting against stops or shoulders 38^a of the head of the cas- 115 ing adjacent which are openings or recesses 38^a to receive the extensions 19^a when the carrier is separated radially and is moved forward. The locking thimble is substan- 120 tially like that first described, this being indi- cated at 30^a and the carrier is grooved at 36^a and has the shoulder 21^a substantially as in the first form. The operation of the device is substantially the same as that in the form first described, the firing pin, how- 125 ever, moving to and contacting with the primer, which is fixed in the casing instead of the primer moving with the carrier to contact with a fixed firing pin.

If desired the sectional firing pin may be provided with a cap member.

Reverting to the primer plate 26 of Fig. 11 it will be understood that the cross form of this plate provides spaces or openings for the flashing of the exploded primer there-
5 through.

What I claim is:—

1. In combination in a safety fuse for projectiles, a casing, a primer carrier or cage composed of radially separable members, said cage being axially movable within the casing and normally held in a forward position in said casing and adapted to assume a position away from its normal location and toward the outer end of the 15 casing due to the firing of the projectile from the gun, means for locking the cage in its outer position, said locking means engaging the members of the cage when they are displaced radially, due to centrifugal 20 force, said cage with its locking means moving forwardly under the force of the impact when the projectile strikes the object and a firing pin to engage the primer when the cage moves forward with its members 25 separated, substantially as described.

2. In combination in a safety percussion base fuse, a firing pin, a primer, a carrier for one of said parts, and a casing, said carrier being normally located at an intermediate 30 point in the casing and slideable both rearwardly and forwardly, and being formed in sections, said carrier having the following cycle of movements due to the firing of the projectile, the centrifugal force 35 derived from the rifling and the impact of the projectile, respectively, namely first an axial movement rearwardly in respect to the casing, a separating movement of its members radially and finally a forward movement, the latter movement causing the primer to be exploded by the firing pin, substantially as described.

3. In combination in a safety fuse, a firing pin, a primer, a sectional carrier or cage 45 normally held in forward position relative to the casing, and carrying one of said parts, a casing, a locking member having frictional contact with the wall of the casing and adapted to engage and temporarily hold the 50 members of the cage against forward movement along the casing, moved rearwardly in respect to the casing and when after being moved radially in respect to each other, said locking means being slideable along the 55 wall of the casing with the cage when the same moves forwardly due to the impact, allowing the firing pin to engage the primer when the cage moves forwardly, substantially as described.

60 4. In combination in a safety fuse, a firing pin, a primer, a sectional carrier within the same normally held in forward position in respect thereto, and carrying one of said parts, a casing, a thimble having means to 65 engage the members of the cage when they

move rearwardly in respect to the casing and radially in respect to each other, said thimble being slideable on the wall of the casing when the cage moves forwardly due to the impact, said firing pin engaging the primer when the cage moves forwardly, substantially as described.

5. In combination in a safety fuse for projectiles, a primer, a firing pin, a carrier for one of said parts composed of radially separable sections, a casing, said carrier being adapted to have axial movement in respect to the casing, a thimble having a flange and seated against the wall of the casing, said flange engaging a portion of the sections of the carrier when said carrier moves rearwardly from normal position in respect to the casing and its sections separate radially, said thimble being slideable forwardly with the cage under the impact of the projectile 85 striking the object causing the firing pin to engage the primer, substantially as described.

6. In combination a casing having a shoulder therein, a thimble seated against said shoulder and bearing on the inner wall of the casing to slide thereon, a carrier normally disposed in a forward position relative to the casing and composed of radially separable sections, said thimble having a portion to engage and temporarily hold the cage when moved rearwardly and separated radially and a firing pin to engage the primer, one of said parts being carried by the carrier when it moves forwardly, said thimble being slideable with the carrier, substantially as described.

7. In combination a casing, a cage composed of separable sections carrying the primer between them, a spring for pressing the cage normally forward in relation to the casing, means for engaging the members of the casing when moved axially to the rear of the casing and separated in respect to each other to temporarily hold the sections in their retracted positions, said engaging means allowing the cage to move forwardly under the impact of the striking projectile and a firing pin against which the primer contacts when the cage moves forwardly, substantially as described.

8. In combination a casing, a sectional primer carrying cage within the same normally disposed in a forward position relative to the casing, means for holding the members of the cage in position when moved axially rearward in respect to the casing and when said members are separated radially, a firing pin, the said holding means allowing the cage to move forwardly under the impact of the striking projectile to bring the primer against the firing pin, substantially as described.

9. In combination, a primer, a firing pin, a sectional carrier for one of said parts, a

casing, said carrier being movable axially of the casing and with its members adapted to separate radially, a shoulder to limit the forward position of the carrier when its members are closed toward each other, means to engage and temporarily hold the members of the cage when moved rearwardly in respect to the casing and radially in respect to each other, the said radial movement of the members removing them from the said shoulder and placing them in position to move forwardly past said shoulder, said engaging means permitting the cage to move forwardly under the impact causing the firing pin to impinge against the primer when the carrier moves forwardly, substantially as described.

10. In combination a casing, a sectional carrier within the casing movable axially thereof and with its members adapted to separate radially, a shoulder to limit the forward position of the carrier when its members are closed toward each other, means to engage and temporarily hold the members of the carrier when moved rearwardly in respect to the casing and radially in respect to each other, the said radial movement of the members removing them from the said shoulder and placing them in position to move forwardly past said shoulder, said engaging means permitting the carrier to move forwardly under the impact, a primer, and a firing pin against which the primer contacts when the cage moves forwardly, said shoulder for determining the normal position of the cage being on the firing pin, substantially as described.

11. In combination a casing, a sectional carrier within the same having a groove and a shoulder, a firing pin and a primer one of which is carried by the carrier, a thimble having a flange at each end to engage the groove and shoulder, respectively, said carrier having its members adapted to separate radially and being located normally in an intermediate position in respect to said casing, the said thimble temporarily holding the members of the carrier when moved rearwardly in respect to the casing and 50 radially outward in respect to each other, and moving with said carrier under the impact of the striking projectile to bring the firing pin and primer together, substantially as described.

12. In combination a casing, a sectional primer carrying cage within the casing, a spring for pressing the cage forwardly, a firing pin surrounded by a portion of the cage and having a shoulder to determine the 60 normal intermediate position of the cage in respect to the casing, said cage moving rearwardly in respect to said casing when the projectile is fired and its members separating radially by centrifugal force due to the 65 rifling, a thimble having frictional contact

with the casing and engaging the members of the cage when moved axially to their rearward position and separated radially to temporarily hold them against forward movement, the separated members of the cage being out of line with the limiting shoulder surrounding the firing pin, the said cage under the impact and while in separated condition moving forward together with the engaging means and in its forward movement causing the primer to contact with the firing pin, substantially as described.

13. In combination in a safety fuse for projectiles, a casing, a primer carrying cage 80 therein normally disposed in an intermediate position, said cage being formed in radially separable sections, means whereby said cage is permitted to move rearwardly in the casing when the projectile is fired 85 and to permit its members to separate radially under centrifugal force, and a firing pin against which the separated cage carries the primer on moving forward due to the impact of the projectile, substantially as described.

14. In combination in a safety fuse for projectiles, a casing, a cage of smaller diameter than the interior of the casing and composed of radially separable sections, 95 said casing having a shoulder against which the cage bears to retain it normally in an intermediate position, means for centering said cage within the casing but allowing the cage sections to separate when it moves to 100 its outward position consequent upon firing the projectile, said cage moving forward under the impact of the projectile past the said shoulder and a firing pin and a primer, one of said last mentioned parts being carried by the cage, substantially as described.

15. In combination in a safety fuse for projectiles, a firing pin member, a primer member, a casing holding one of said members, a carrier for the other of said members 110 composed of radially separable parts, said carrier being axially movable within the casing and normally held in a forward position in said casing and adapted to assume a position away from its normal location and toward the outer end of the casing due to the firing of the projectile from the gun, means for locking the carrier in its outer position, said locking means engaging the members of the carrier, when they are 115 displaced radially, due to centrifugal force, said carrier with its locking means moving forwardly under the force of impact when the projectile strikes the object to cause the firing pin to explode the primer, substantially as described.

In testimony whereof, I affix my signature.

HUBERT MEREDITH-JONES.
